(57) **CLAIM**

The ornamental design for an open canopy roof, as shown and described.

DESCRIPTION

FIG. 1 is a top, front end, and left side perspective view of an open canopy roof, the rear end and right side are essentially mirror images of the front end and left side as shown in FIG. 1.

FIG. 2 is an enlarged fragmentary end perspective view of the open canopy roof, of FIG. 1.

FIG. 3 is an enlarged fragmentary top perspective view of a portion of the open canopy roof illustrated in FIG. 1.

FIG. 4 is an enlarged fragmentary perspective view of the underneath of the open canopy roof, illustrating the open modular framing structure of FIGS. 1-3; and,

FIG. 5 is an enlarged fragmentary perspective end view illustrating a portion of the underneath of the framing structure of the open canopy roof of FIGS. 1-4.

The parking area, the automobiles, the light standards and lights shown in broken lines under the framing structure all do not form part of the design of this invention, but illustrate environment only.
